(57) **CLAIM**

We claim an ornamental design for a liquid crystal television receiver including a tuner mounted thereon, as shown and described.

DESCRIPTION

FIG. 1 is a FRONT ELEVATIONAL view of a liquid crystal television receiver including a tuner mounted thereon showing our new design;

FIG. 2 is a TOP PLAN view thereof;

FIG. 3 is a BOTTOM PLAN view thereof;

FIG. 4 is a LEFT ELEVATIONAL SIDE view thereof;

FIG. 5 is a RIGHT ELEVATIONAL SIDE view thereof; and,

FIG. 6 is a BACK ELEVATIONAL view of the same.

1 Claim, 5 Drawing Sheets
